APPARATUS FOR FOLDING FLEXIBLE
ARTICLES AND THE LIKE

Frederic B. Clark, Englewood, N. J.

Application October 15, 1937, Serial No. 169,292

8 Claims. (Cl. 270—68)

My present invention relates to apparatus or machines adapted for use particularly, but not exclusively in connection with flat work ironers, to receive articles of laundry or the like such as 5 towels, napkins, handkerchiefs and to effect folding thereof transversely, and longitudinally, if desired, in the same forms as now done by hand.

The invention provides a relatively simple and compact structure operated at a minimum cost, 10 and which is adjustable or adaptable to handle articles of varying lengths and widths.

Stated generally, the invention resides in the provision of means to successively feed or advance the articles so that their forward edges or 15 ends will contact an abutment which causes the articles to partially fold upon themselves, so that a fold is created and received by a driven roller or between a pair of rollers, as will hereinafter be pointed out in detail. Successive abutments 20 and rollers to cause folding in one direction may be provided to effect several folds. A relatively narrow carrier or endless belt to effect folding in another direction at right angles to the fold effected by the rollers and abutments may be 25 provided.

The foregoing and other objects and advantages of the invention will be pointed out in detail during the course of the following description of the accompanying drawings in which;

30 Fig. 1 is a side elevation of a machine embodying the present invention and a fragment of the end of a flat work ironer.

Fig. 2 is a top plan view of the machine shown in Fig. 1.

35 Fig. 3 is a view taken on line 3—3 of Fig. 1; and

Figs. 4, 5 and 6 are perspective views of an article showing the different stages of folding.

Referring to the drawings in detail, the number 40 7 designates generally the delivery end of the flat work ironer, of any known construction, it being understood that the articles to be folded are received by and carried along the belt or other means, 8, in the direction indicated by 45 the arrows in Fig. 1. The folding apparatus is arranged adjacent to the delivery end of the flat work ironer to receive the articles successively therefrom.

In the form of the invention shown in Fig. 1, 50 provision is made for effecting two transverse folds, that is, to fold a flat article once upon itself as illustrated in Fig. 4 and then again upon itself as shown in Fig. 5, so that it may subsequently be folded longitudinally as shown in Fig. 55 6. It will become apparent that the number of

transverse folds may be single, double, triple, etc., and that the longitudinal folding may be dispensed with, if desired. In the drawings the numeral 9 designates the articles to be folded.

The letter F designates generally the frame of the folding machine, to one end of which is secured a trough, 10, as by means of bolts or screws, 11, or other suitable elements which will permit adjustment of the trough to any desired position. The trough is preferably of the same width as the delivery end of the flat work ironer and the lower portion of the trough comprises a curved plate or portion 12, on to which the approaching ends of the articles are delivered for movement thereagainst along to the abutment or stop 13, 15 at the end of the trough. It is possible to effect adaptability of the apparatus to articles of different lengths or sizes by inserting removable stops 13, of varying widths as will become presently more apparent. The upper end of the plate 12 terminates in proximity to roller 15, which is also substantially the same length as the width of trough 10 and delivery end of the flat work ironer, and keyed to shaft 16 driven by pulley 17. Belt 18 is trained around pulley 17 and pulley 19 driven by reduction gear motor 20. Pulley 17 is provided with two grooves, one receiving belt 18 and the other belt 21. The belt 21 drives pulley 22 keyed to shaft 23, to which shaft roller 24 is keyed. A belt 25 is trained around pulleys 22 and 26, keyed to shaft 27, driving roller 28 above roller 24. A fourth belt 29, is trained around pulley 26 and pulley 30 on the shaft 31, to which is keyed roller 32 above roller 15. 35

The rollers 15 and 32 cooperate to complete the first fold and to pass the article on for the second folding, although roller 15 alone may be used, and the second pair of rollers dispensed with. The fold or folds are termed the transverse folds; although if the article is delivered 40 with its approaching edge constituting the length, the folds thus effected may be termed longitudinal with respect to the article itself as distinguished from the folds effected by the machine and being described herein as transverse 45 and longitudinal relative to the machine.

Assuming, for the purpose of illustration, that the flat work ironer is delivering towels thirty-six inches in length, the abutment or stop 13 in trough 10 would be so adjusted or spaced with 50 relation to the crevise between rollers 15 and 32, or top of roller 15, that the approximate center of the towel or article would reach said crevise, or top of roller 15, when the approaching end of the towel met abutment 10. Thus the towel 55

would be folded once upon itself in the condition shown in Fig. 4, after passing between the rollers 15 and 32, or over 15. When the approaching end of the towel or other article meets abutment 5 13, the towel or article sags or partly folds upon itself so that it is gripped between the rollers 15 and 32 and passed to the next folding operation if such further folding is desired, or on to delivery mechanism of any desired type if no 10 further fold is desired.

In the present application, and in Fig. 1, I have shown means for effecting a second folding of the towel between rollers 24 and 28 in the same manner as the towel or article was originally folded between rollers 15 and 32, and abutment 15 13. To effect this a second trough 34, similar to trough 10 is arranged beneath roller 15 and between rollers 15 and 24, and is preferably supported by an adjustable bracket 35 secured to 20 the frame F by any suitable means. When the towel or other article folded once upon itself is delivered over roller 15, the crease or folded edge slides down trough 34 until it strikes abutment 36 at which time the rollers 24 and 28 grip the 25 once folded article at its approximate center and effect a second fold which places the article in the condition shown in Fig. 5, that is in four layers.

If further folding, such as longitudinal folding 30 to place the article in the condition shown in Fig. 6 is desired, I provide a narrow carrier such as an endless belt on to which the article is delivered by rollers 24 and 28. This belt is shown best in Figs. 1 and 2, located centrally and longitudinally of the frame, and is trained around a pulley 37 located between notches 38 in the center of rollers 24 and 28. The notches are furnished to provide for clearance of the belt as the folded articles pass between rollers 24 and 35 40 28. The belt is also trained around a pulley 39, at the outlet or the discharge end of the apparatus, and is supported on a shaft 40, journaled between brackets or supports 41 at opposite sides of the frame. An idler pulley 42 is preferably 45 provided to engage the lower flight of the belt. Pulley 42 is normally urged or forced against the belt to maintain proper tension by any suitable means such as a spring on shaft 43 supporting the frame 44 on the outer end of which the pulley 42 is journaled.

The belt referred to constitutes a narrow member extending at approximately a right angle from a point adjacent to the position of emergence of the folded flexible sheet article from the 50 55 pair of coacting rollers. The upper reach of this member moves in direction away from the said position and is adapted to convey the folded article away from the rollers.

I claim:

60 1. An apparatus of the character described for folding flexible articles, means to receive the articles and to advance them, an abutment for contact by the approaching ends of the articles to retard their advance, a pair of rollers to grip the article as it partially folds upon itself as determined by the location of said abutment relative to said pair of rollers to effect folding and further advancement of the articles and a relatively narrow carrier extending at approximately a right angle to the axes of the said pair of rollers, to receive said articles from said rollers to effect folding transversely to the fold effected by said rollers and abutment.

70 2. An apparatus of the character described for folding flexible articles, means to receive the

articles and to advance them, an abutment for contact by the approaching ends of the articles to retard their advance, a pair of rollers to grip the articles as they partially fold upon themselves, a second abutment to retard the partially folded articles, and a second pair of rollers to effect folding and further advancement of the articles and a relatively narrow carrier extending at approximately a right angle to the axes of the second pair of rollers to receive said articles from said second rollers and to effect folding transversely to said first folds.

3. An apparatus of the character described for folding flexible articles, means to receive the articles and to advance them, an abutment for contact by the approaching ends of the articles to retard their advance, a pair of rollers to grip the article as it partially folds upon itself as determined by the location of said abutment relative to said pair of rollers to effect folding and further advancement of the article, and other rollers and intermediate abutments to effect further folding in the manner specified and a relatively narrow conveyor to receive the thus folded articles and effect further folding thereof transversely to the direction of fold created by said rollers and abutments.

4. A machine for folding a flexible fabric sheet, comprising a chute of width at least approximately equal to that of the sheet to be folded, means for delivering the sheet edgewise to the upper part of the chute, means to stop the movement of the sheet down the chute before all of the sheet has been delivered thereto, so as to produce buckling of the sheet at a position above the upper part of the chute and in advance of the means for delivering the sheet to the chute, and a pair of coacting rollers for engaging the buckled portion of the sheet and pressing the buckled portion, to cause folding.

5. A machine for folding a flexible sheet article, comprising means for delivering the article and allowing it to descend edgewise under the influence of gravity, means for initiating a horizontal fold in the article when the forward edge thereof has descended to a predetermined distance, and a pair of coacting driven rollers for engaging the said fold and pressing it.

6. A machine for folding a flexible sheet article comprising: means for delivering the article and allowing it to descend edgewise under the influence of gravity; means for initiating a horizontal fold in the article when the forward edge thereof has descended to a predetermined distance; a pair of coacting driven rollers for engaging the fold and passing the folded article therebetween; a narrow member terminating at a location adjacent to the position of emergence of the folded article from the rollers, so as to receive the folded article, the said member extending at approximately a right angle to the axes of the rollers; and means for moving the folded article, while suspended over the said member, away from the rollers.

7. A machine as described in claim 6, the means for moving the folded article away from the rollers including a driven belt contacting with the folded article.

8. A machine as described in claim 5, the rollers being provided in the central portion thereof with a notch and the machine including a driven belt extending through the notch for removing the folded article from the said rollers.

CERTIFICATE OF CORRECTION.

Patent No. 2,195,716.

April 2, 1940.

FREDERIC B. CLARK.

It is hereby certified that error appears in the above numbered patent requiring correction as follows: In the grant, line 15, for "Frederic C. Clark, his heirs" read --Frederic B. Clark, his heirs--; and that the said Letters Patent should be read with this correction therein that the same may conform to the record of the case in the Patent Office.

Signed and sealed this 9th day of July, A. D. 1940.
